(57) **CLAIM**

The ornamental design for a bathing tub, as shown and described.

DESCRIPTION

FIG. 1 is a front elevational view of a first embodiment of the bathing tub;

FIG. 2 is a rear elevational view of the bathing tub of FIG. 1;

FIG. 3 is a left side elevational view of the bathing tub of FIG. 1;

FIG. 4 is a right side elevational view of the bathing tub of FIG. 1;

FIG. 5 is a top plan view of the bathing tub of FIG. 1;

FIG. 6 is a bottom plan view of the bathing tub of FIG. 1;

FIG. 7 is a front perspective view of the bathing tub of FIG. 1;

FIG. 8 is a rear perspective view of the bathing tub of FIG. 1;

FIG. 9 is an environmental view of the bathing tub of FIG. 1 in combination with a lid;

FIG. 10 is a front elevational view of a second embodiment of the bathing tub;

FIG. 11 is a rear elevational view of the bathing tub of FIG. 10;

FIG. 12 is a left side elevational view of the bathing tub of FIG. 10;

FIG. 13 is a right side elevational view of the bathing tub of FIG. 10;

FIG. 14 is a top plan view of the bathing tub of FIG. 10;

FIG. 15 is a bottom plan view of the bathing tub of FIG. 10;

FIG. 16 is a front perspective view of the bathing tub of FIG. 10;

FIG. 17 is a rear perspective view of the bathing tub of FIG. 10; and,

FIG. 18 is an environmental view of the bathing tub of FIG. 10 in combination with a lid.

The broken-line disclosure of elements is understood to represent portions of the article in which the design is embodied, but which form no part of the claimed design.

1 Claim, 18 Drawing Sheets
